UNITED STATES PATENT OFFICE.

WALTER S. OLSON, OF BROWNSDALE, MINNESOTA.

FLYING TOY BIRD.

964,803.

Specification of Letters Patent. Patented July 19, 1910.

Application filed April 12, 1909. Serial No. 489,386.

To all whom it may concern:

Be it known that I, WALTER S. OLSON, a citizen of the United States, residing at Brownsdale, in the county of Mower, State 5 of Minnesota, have invented certain new and useful Improvements in Flying Toy Birds; and I do hereby declare the following to be a full, clear, and exact description of the invention, such as will enable others skilled in 10 the art to which it appertains to make and use the same.

This invention relates to toys formed to represent a flying bird, and has for one of its objects to produce a toy which when actuated imitates the flying movements of a 15 bird.

With this and other objects in view, the invention consists in certain novel features 20 of construction as hereafter shown and described and then specifically pointed out in the claim, and in the drawings illustrative of the preferred embodiment of the invention.

Figure 1 is a side elevation of the improved device. Fig. 2 is a longitudinal sectional elevation of the same. Fig. 3 is a transverse section on the line 3—3 of Fig. 2.

The improved device comprises a light hollow body 10, preferably formed of light sheet metal, and conforming to the outlines 30 of a bird. Located in the lower portion of the body 10 is a counter-weight 11 of sufficient weight to maintain the body in a vertical position as hereafter explained. Extending transversely within the body 10 is 35 a shaft 12 having two cranks 13—14 therein intermediate the ends and with two or more springs 15 connected thereto and operating to retain the shaft yieldably in one position, and to return it to that position, as hereafter 40 explained. Pivoted at 16—17 are the representations of wings 18—19, the pivoting of the wings permitting them to be moved outwardly and inwardly in imitation of the natural movements of the wings. The wings 45 are provided with inwardly extending arms 20—21, the wings being connected respectively by rods 22—23 to the cranks 13—14. By this means it will be understood that when the shaft 12 is rotated the wings will be 50 caused to swing upon their pivots and thus imitate the natural movements of the wings. Connected to the shaft 12 is a drum 24 to which one end of a cord or cable 25 is con-

nected. The cord 25 extends through an aperture 26 in the body 10 and is provided 55 at its free end with a hook 27 adapted to be connected as by an eye 28 to a stationary structure 29. The stationary structure may be a wall, a post, a tree, or other object, in convenient position for the operator. Connected 60 at 30 to the body 10 in advance of the shaft 11 is another cord or cable 31, the latter leading to any required distance and provided with a finger loop 32.

The springs 15 it will be understood are 65 arranged to be maintained normally in their unwound position, and to consequently maintain the cord or cable 25 normally wound upon the drum 24, and then when a pull strain is applied to the cord 31 the 70 "bird" 10 is drawn toward the operator and the cord 25 and the springs 15 unwound, and when the cord 31 is released the recoil of the springs 15 again winds the cord 25 upon the drum and moves the "bird" toward 75 the stationary structure 29. Then by again drawing upon the cord 31 the action is repeated, and so on as often as required, the "bird" being thus constructed to pursue a flight in imitation of the natural "flight" of 80 birds. At each motion of the "bird" the rotation of the shaft 12 is communicated through the cranks 13—14 and rods 22—23 to the wings 18—19, as will be obvious. The motion thus closely imitates the natural 85 flight of the bird and amuses and interests the operator.

The body 10 may be formed in the imitation of any of the various birds, and of any desired size, and of any suitable material. 90

The improved device is simple in construction, can be inexpensively manufactured, and operated by small children without the necessity of previous skill or experience.

What is claimed, is:—

The herein described flying toy comprising a hollow body, wings on the sides thereof of having arms extending inwardly through and pivotally mounted in the sides of the body the pivots of said wings being parallel 100 with the axis of the body; a transverse shaft having its bearings in the sides of the body and provided with a centrally disposed drum and with cranks on opposite sides of the drum, rods connecting said cranks and 105 the inner ends of the arms of the wings, a

cord extending rearwardly through and from the body and connected to the drum, a spring connected to the body and the shaft and acting to revolve the latter and the drum to wind said cord on said drum, and a pull cord attached to the front portion of the body.

In testimony whereof, I affix my signature, in presence of two witnesses.

WALTER S. OLSON.
